US00D718601S

(12) **United States Design Patent**
Beyer

(10) **Patent No.:** **US D718,601 S**
(45) **Date of Patent:** **** Dec. 2, 2014**

(54) **ABRASIVE ARTICLE**

(75) Inventor: **Timothy T. Beyer**, Artarmon (AU)

(73) Assignee: **3M Innovative Properties Company**,
Saint Paul, MN (US)

(**) Term: **14 Years**

(21) Appl. No.: **29/419,428**

(22) Filed: **Apr. 27, 2012**

(30) **Foreign Application Priority Data**

Oct. 31, 2011 (EM) ..... 1300057 - 1/3

(51) **LOC (10) Cl.** **08-05**

(52) **U.S. Cl.**

USPC **D8/90; D5/57**

(57) **CLAIM**

The ornamental design for an abrasive article, as shown and described.

DESCRIPTION

FIG. 1 is a perspective view of an abrasive article showing an ornamental design in accordance with the present disclosure. FIG. 2 is a top view of the abrasive article of FIG. 1; FIG. 3 is a bottom view of the abrasive article of FIG. 1; FIG. 4 is a front side view of the abrasive article of FIG. 1; and, FIG. 5 is a left side view of the abrasive article of FIG. 1. The rear side view is identical to the front side view. The right side view is identical to the left side view. The broken lines shown in FIGS. 1-5 form no part of the claimed design.

1 Claim, 2 Drawing Sheets
